CHAIR

Donald T. Chadwick, 1812 Melhill,
Los Angeles, Calif. 90049

Filed Feb. 8, 1971, Ser. No. 113,782

Term of patent 7 years

Int. Cl. D6—02

U.S. Cl. D6—78

FIG. 1 is a perspective view of one embodiment of the chair of my novel design;

FIG. 2 is a side elevational view taken from the side of FIG. 1, not exposed;

FIG. 3 is a top plan view of chair shown in FIG. 1;

FIG. 4 is a rear view of the chair shown in FIG. 1;

FIG. 5 is a bottom plan view of the chair shown in FIG. 1;

FIG. 6 is a perspective view of a second embodiment of the chair of my novel design, incorporating arms;

FIG. 7 is a side elevational view taken from the unexposed side of FIG. 6;

FIG. 8 is a rear elevational view of the chair shown in FIG. 6; and

FIGS. 9 and 10 are top and bottom plan views, respectively, of the chair shown in FIG. 6.

I claim:

The ornamental design for a chair, as shown.
